UNITED STATES PATENT OFFICE.

FORD, W. HARRIS, OF WILKINSBURG, PENNSYLVANIA, ASSIGNEE, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

CIRCUIT-INTERRUPTER.

1,481,789.

Specification of Letters Patent.

Patented July 9, 1912.

Application filed March 9, 1908. Serial No. 420,063.

To all whom it may concern:

Be it known that I, FORD W. HARRIS, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters, and it has for its object to provide a device of this character that shall be relatively simple and inexpensive in construction and adapted for use with very high-voltage circuits and for installation in the open air.

In the prior art, interrupters for high-voltage polyphase circuits could not be safely and successfully operated in the open air under adverse weather conditions, by reason of the tendency of the electric currents to creep over wet surfaces. It has been my aim to design a circuit-breaker for accomplishing this result without sacrificing either simplicity and economy in construction or sensitiveness and efficiency in operation.

According to my present invention, I provide a plurality of independent inclosing casings in which the main operating mechanism and a number of groups of co-operating stationary and movable contact members are severally disposed. The casings are weather-proof and are separated by material distances, the only connection between them, aside from a common supporting structure, being formed by pipe sections through which an actuating rod extends. The lower parts of the casings are removable and are made in the form of tanks to contain a suitable insulating fluid.

Figure 1 of the accompanying drawings is a side elevation of a portion of a circuit interrupter constructed in accordance with my invention, the inclosing casings being shown in section to disclose the operating parts. Fig. 2 is a sectional elevation through one of the casings of Fig. 1, and Fig. 3 is an outline view of the assembled circuit interrupter which brings out more clearly the relation between the different groups of co-operating contact members.

Referring to the drawings, the device here illustrated comprises a stationary frame 1,

a plurality of inclosing casings 2, 3, 4 and 5, stationary contact members 6 and 7, a movable contact member 8, an operating mechanism 9 and a plurality of leads 10 and 11. The casings 3, 4 and 5 are similar to each other and each contains a pair of stationary contact members, a movable contact member and such portion of the operating mechanism 9 as is directly associated with said movable member. Since similar parts are found in each casing, only one group will be described in detail by reference to Figs. 1 and 2 of the drawings.

The leads 10 and 11 are directly connected to one phase of the circuit controlled by the breaker and are supported by a cover member 12 from which they are carefully insulated by means of bushings 13. The bushings 13 may be constructed in any suitable manner and may support, at their lower extremities, the stationary contact members 6 and 7. In order that the line conductors, which are joined to the outer extremities of leads 10 and 11, may be widely separated from each other, the leads are supported obliquely, their lower extremities being brought relatively close together with safety since, at this point, they are separated by the insulating fluid contained in the tank. The portions of the insulating bushings which are without the tanks are protected from the weather by a plurality of insulating bells or flanges 14.

The stationary contact members make butt joints with the movable contact members, but the latter are provided with terminal pieces 28 which are resiliently connected to the body portions of said members, the electrical connection between the two parts being improved by a flexible shunt 29. The terminal pieces 28 are permitted to move only within predetermined limits along the center lines of the stationary terminals. Since these lines are oblique, as above indicated, a sliding contact is effected between the engaging surfaces as the movable contact members engage the stationary members or are separated from them.

The operating mechanism 9 comprises a main operating lever 30 which may be actuated by hand or otherwise, a rod 32 which interconnects the operating levers for the several groups of contact members, and a

bell crank lever 31 which is interposed between the lever 30 and the connecting rod 32.

Each of the movable contact members 8 is connected to the lower extremity of a vertical rod 33, the upper extremity of which is connected to one end of a lever 34. The lever 34 is connected to a stationary pivot 35 by a link 36 and is operatively connected to the rod 32 by means of a bell crank lever 37 which is fulcrumed upon a stationary shaft 38. The bell crank lever 37 is provided with a projection 39 to which a spring 40 is secured and its respective main arms are connected to an intermediate point in the lever 34 and to the rod 32. One end of the spring 40 is secured to a stationary part of the device and is adapted to assist the operating lever 30 in raising the movable contact members into engagement with the stationary members.

Parts corresponding to those indicated by reference characters 33, 34, 36, 37 and 40 are found in each of the inclosing casings 3, 4 and 5 and the bell crank lever 31 is located in the casing 2. The rod 32, which connects the bell crank lever 31 to the bell crank lever 37, is protected from the weather by pipe sections 41, 42 and 43 in which it operates freely.

One arm of the bell crank lever 31 is provided with a roller 44 which may be engaged by a latch 45 when the circuit interrupter is closed. This latch forms a part of a bell crank lever 46 the position of which is controlled manually by a lever 49, by the action of gravity upon a weight 47, or by a magnet winding 48. The magnet winding 48 receives its energy from an auxiliary circuit which may be supplied from any suitable source when the main circuit current exceeds a predetermined amount.

Assuming that the movable contact members are disengaged from the stationary members, the circuit interrupter may be closed by a downward movement of the operating lever 30. This action produces a rotative movement of the bell crank lever 31 through an angle of substantially 90° and imparts a longitudinal movement to the rod 32. This motion is transmitted to the vertical rods or shafts 33 by the levers 37 and 34.

It will be understood that structural modifications may be effected within the scope of my invention, and I desire that only such limitations shall be imposed as are indicated in the appended claims.

I claim as my invention:

1. In a circuit interrupter, the combination with a plurality of interchangeable groups of stationary and movable contact members, inclosing casings for the respective groups and operating mechanisms located within the casings, of a main actuating mechanism comprising an independent inclosing casing, an operating lever, a latch and a tripping means located within the casing, and means for interconnecting the operating mechanisms and the main actuating mechanism. 70

2. In a circuit interrupter, the combination with a plurality of interchangeable groups of stationary and movable contact members, inclosing casings for the respective groups and operating mechanisms located within the casings, of a main actuating mechanism comprising an independent inclosing casing, a bell crank lever, a latch therefor and a tripping means, located within the casing, operating and release handles 80 extending through the walls of the casing, and a rod that connects the operating mechanisms to the bell crank lever. 75

3. In a circuit interrupter, the combination with a plurality of groups of stationary and movable contact members, operating mechanisms and inclosing casings for the respective groups, and interconnecting means for the several operating mechanisms, of a main actuating means for effecting a 85 simultaneous action of the operating mechanisms, an independent inclosing casing therefor, and pipe or tube sections between the adjacent inclosing casings through which the interconnecting means operates. 95

4. In a circuit interrupter, the combination with a plurality of groups of stationary and movable contact members, inclosing casings for the respective groups, and operating mechanisms located within the casings 100 and comprising shafts, bell crank levers and connecting links, of a main actuating mechanism, an independent inclosing casing therefor, a substantially horizontal rod that connects the actuating mechanism with the 105 bell crank levers, and pipe or tube sections between adjacent casings through which the interconnecting rod operates.

In testimony whereof, I have hereunto subscribed my name this 21st day of February, 1908.

FORD W. HARRIS.
